UNITED STATES PATENT OFFICE

158,645

ROAST RACK

John Clark Brown, Upper Montclair, N. J.

Application December 14, 1948, Serial No. 150,145

Term of patent 14 years

(Cl. D44—29)

To all whom it may concern:

Be it known that I, John Clark Brown, a citizen of the United States, residing at No. 18 Waterbury Road, Upper Montclair, county of Essex and State of New Jersey, have invented a new, original, and ornamental Design for a Roast Rack, of which the following is a specification, reference being had to the accompanying drawing, forming part thereof.

In the drawing:

The sole figure is a perspective view of a roast rack showing my new design.

I claim:

The ornamental design for a roast rack, as shown.

JOHN CLARK BROWN.
